UNITED STATES PATENT OFFICE.

PAUL M. LOCKWOOD, OF KANSAS CITY, MISSOURI.

DESIGN FOR A TIRE-COVER.

56,071.

Specification for Design.

Patented Aug. 10, 1920.

Application filed April 17, 1919. Serial No. 290,864. Term of patent 7 years.

To all whom it may concern:

Be it known that I, PAUL M. LOCKWOOD, a citizen of the United States, residing at Kansas City, in the county of Jackson and State of Missouri, have invented a new, original, and ornamental Design for a Tire-Cover, of which the following is a specification, reference being had to the accompanying drawing, forming part thereof.

The figure is a perspective view of a tire cover, showing my new design.

The design consists of annular side mem-

bers 1 and 2 connected by a band 3, in the field of which are spaced smaller fields 4; the band 3 being bounded by stripes 5 and 6. The annular side members and the band 3 are of the same color while the smaller fields 4 and the stripes 5 and 6 are of the same color but differently colored from the annular side members and the band 3.

I claim:

The ornamental design for a tire cover as shown and described.

PAUL M. LOCKWOOD.
